UNITED STATES PATENT OFFICE.

SUMNER B. SARGENT, OF HUNTINGTON PARK, CALIFORNIA.

PUMP CONNECTION.

Application filed July 19, 1924. Serial No. 727,027.

To all whom it may concern:

Be it known that I, SUMNER B. SARGENT, a citizen of the United States, residing at Huntington Park, in the county of Los Angeles and State of California, have invented a new and useful Pump Connection, of which the following is a specification.

This invention relates to pump connections of the type employed with deep well pumps.

It is customary in hooking up the pump to the walking beam to so connect the pump that the upper face of the walking beam is substantially horizontal when the pump plunger is substantially half way between the upper and lower ends of its stroke. This results in the polish rod being bent to one side of the axis of the pump to a greater degree when the plunger is making the upper half of its stroke than when making the lower half of said stroke.

An object of this invention is to provide a connection between the pump and walking beam that will insure that the polish rod will not, as above described, be bent out of line to a greater degree at the upper portion of its stroke than at the lower portion, thus minimizing wear on the polish rod and stuffing box.

A further object is to provide a connection of this character of comparatively simple construction.

The accompanying drawings illustrate the invention.

Figure 1 is a side view of a pump connection constructed in accordance with the provisions of this invention and mounted on a walking beam, a fragment of which is shown. A fragment of the stanchion pivotally supporting the walking beam is also shown.

Fig. 2 is an enlarged sectional elevation on the line indicated by 2-2 Fig. 1.

The pump connection comprises a pair of members disposed on the opposite sides of the walking beam, indicated at 3, and extending below the under face thereof. Each of these members comprises a flat member 4, a hollow cylindrical boss 5 at one end of the member 4, a hollow cylindrical boss 6 at an intermediate portion of said member 4 and a pair of spaced cylindrical bosses 7 at the lower end of the member 4. The boss 6 is positioned eccentric to a line connecting the bosses 5, 7 and for this reason the member 4 is widened sufficiently to obtain

this result. In this particular instance the member 4 has a straight portion 8 at the opposite ends of which are the bosses 5, 7, and said member 4 also has an arcuate portion 9 connected at its ends to the straight portion 8. The boss 6 is near the middle of the portion 9.

Lag screws 10 may be employed to first fasten the members 4 in position on opposite sides of the walking beam 3, but said lag screws are not intended to sustain any of the load supported by the members 4 as said load is taken by the bosses 5 seated on the upper face 11 of the walking beam. The inner ends of the bosses 5 substantially meet and a bolt 12 passes through the bores of the bosses 5 to securely hold the members 4 toward one another. The bosses 6 seat against the under face 13 of the walking beam and a bolt 14 passes through the bores of the bosses 6. The bosses 7 of opposed members 4 are designed to hold a pin or bolt, not shown, connecting them, which pin or bolt supports the usual beam hanger that connects with the polish rod of the pump.

The distance of the bosses 7 from the bosses 5 is sufficient to bring the bosses 7 substantially on a level with the fulcrum point 15 of the walking beam when the upper face of the walking beam is substantially level, and when the pump is connected with the walking beam by the use of this invention, the axis of the bosses 7 is the axis about which the beam hanger turns as the walking beam swings up and down.

In connecting up the pump with the walking beam by the use of this invention, the pump plunger will be in the middle of its stroke when the upper face of the walking beam is substantially level as in Fig. 1 and thus, in operation, the walking beam will operate the same distance above the position of Fig. 1 as below, and, accordingly, the polish rod will be bent equal amounts to one side of the axis of the pump when the pump plunger is at the upper and lower ends of its stroke.

The bosses 6 are for the purpose of resisting the lateral thrust of the pump hanger as the walking beam operates, and the eccentric positioning of said bosses in reference to a line connecting the bosses 5, 7 is for the purpose of bringing the bosses 6 far enough from the pump end of the walking beam to clear the slot 16 through which a portion of the pump hanger projects.

I claim:

1. A pump connection comprising a pair of members having hollow bosses at their upper ends adapted to seat on an operating member, and a bolt extending through the bosses, said members having other hollow bosses at their lower ends for receiving a pin.
2. A pump connection comprising a pair of members having hollow bosses at their upper ends adapted to seat on an operating member and having other hollow bosses at intermediate points adapted to seat against the under face of the operating member, and bolts extending through the bosses, said members having other hollow bosses at their lower ends for receiving a pin.
3. A pump connection comprising a pair of members having means at their upper

ends to engage an operating member, said first members extending below the under face of said operating member, means at the lower ends of said first members for connecting with a pump hanger, and means on said first members for engaging the under face of the operating member.

4. The combination with a walking beam, of members secured near one end of the walking beam against swinging and extending below the under face of the walking beam, and means on said members substantially on a level with the fulcrum point of the walking beam when the upper face of the walking beam is level for connecting said members with a pump hanger.

Signed at Los Angeles, California, this 11th day of July, 1924.

SUMNER B. SARGENT.
